UNITED STATES PATENT OFFICE.

FREDERICK H. LOVERIDGE, OF CHICAGO, ILLINOIS, ASSIGNOR TO
WESTERN ELECTRIC COMPANY, OF CHICAGO, ILLINOIS, A COR-
PORATION OF ILLINOIS.

KEY FOR TELEPHONE-SWITCHBOARDS.

No. 800,747.

Specification of Letters Patent.

Patented Oct. 3, 1905.

Application filed December 12, 1902. Serial No. 134,941.

To all whom it may concern:

Be it known that I, FREDERICK H. LOVE-
RIDGE, a citizen of the United States, residing
at Chicago, in the county of Cook and State
5 of Illinois, have invented a certain new and
useful Improvement in Keys for Telephone-
Switchboards, of which the following is a full,
clear, concise, and exact description.

My invention relates to a switch-key, and
10 has for its object more particularly to provide
an improved structure which will be especially
adapted for use as a party-line ringing-
key to be mounted in the horizontal key-
shelf of a telephone-switchboard.

15 One form of ringing-key which has hereto-
fore been largely used in telephone-switch-
boards has been constructed with vertically-
movable plungers which carry wedges for the
actuation of the switch-springs and which
20 are furnished with buttons on the top of the
key-shelf, by which they may be depressed.
Switchboard-keys should be easy to manipu-
late, so that they will not unduly tire the op-
erator; but an objection to the plunger-oper-
25 ated keys above mentioned has been that they
are very liable to be accidentally actuated
when struck by plugs which are withdrawn
from the jacks by the operator and allowed
to fall upon the key-shelf. When a ringing-
30 key of a cord-circuit over which conversation
is being carried on is thus struck, a violent
crack is produced in the telephones in the
circuit, which is extremely disagreeable and
interrupts the conversation. It has further
35 been common to construct ringing-keys so
that the particular plunger depressed will be
held down by a magnet to apply the calling-
current continuously until the called party
answers, when the magnet is deenergized and
40 releases the plunger. Ringing-keys thus con-
structed have heretofore been somewhat bulky
and the parts necessarily arranged so as not
to be readily accessible for the purposes of
inspection and repair. A further defect has
45 been that it was not easy for the operator to
see by looking down upon the key-shelf
which of the several plungers of a party-line
ringing-key had been depressed, and it is de-
sirable that this should be apparent to the
50 operator at a glance.

My invention was designed to provide a
simple and extremely compact ringing-key

in which these several defects of prior keys
would be eliminated.

The principal characteristic of my key is 55
that each set of switch-springs instead of be-
ing actuated by depressing a plunger is ac-
tuated instead by a cam rotatable upon a ver-
tical axis, a crank-lever being provided upon
the face of the key-shelf which may be turned 60
to rotate said cam. With actuating mechan-
ism of this character the keys will be unaf-
fected by pressure on the top, as by plugs
falling on them. They will be more easily
operated than the old plunger-keys, and the 65
operator can always tell at a glance which
key has been actuated, because the crank-
lever will be turned to an angular position,
thus serving, in effect, as a pointer.

In the preferred form of my invention the 70
ringing-key comprises a number of vertical
shafts mounted in a row in a suitable sup-
porting-frame with the sets of switch-springs
mounted parallel with the corresponding
shafts, said springs being held edgewise in 75
transverse vertical slots at the bottom of the
frame and an actuating-cam carried by each
shaft to move the switch-springs when the
shaft is rotated. I further preferably add a
sticking-magnet, which may be constructed 80
with a single elongated coil of wire wound in a
core of E-shaped cross-section, said core thus
presenting three polar faces, which lie along-
side the row of shafts. Each shaft may then
carry a vertical bar-armature which when the 85
shaft is rotated will be swung laterally over
against the magnet-poles, whereby the key
will be held in its actuated position during the
excitation of the magnet.

I will describe my invention particularly 90
by reference to the accompanying drawings,
which illustrate a key constructed in accord-
ance therewith, and the features or combi-
nations which I regard as novel will be set
forth in the appended claims. 95

Figure 1 is a view of the key in elevation.
Fig. 2 is a plan view thereof. Fig. 3 is a
sectional view on line 3 3 of Fig. 1. Fig. 4
is an end view, and Fig. 5 is a view in cross-
section on line 5 5 of Fig. 1. 100

The same letters of reference are used to
designate the same parts wherever they are
shown.

The key illustrated is a party-line ringing-

key having five sets of switch-springs for applying specialized ringing-current to selectively operate the substation call-bells of telephone-lines, the key being intended to be mounted in the horizontal key-shelf of the central-office switchboard in association with an operator's plug-circuit. Five actuating-shafts *a a* are therefore shown mounted vertically to rock in bearings in the framework *b*, each shaft carrying at the top above the face of the supporting-frame a fin-shaped crank-lever which is adapted to be pulled by the finger of the operator, as shown in Figs. 1 and 2, to rotate the shaft. Each shaft *a* carries an insulating cam-piece *a'* to actuate a corresponding set of switch-springs *c* when the shaft is rotated. The shafts are mounted at intervals in a line along the framework, and the corresponding sets of switch-springs are preferably held edgewise in the transverse vertical slots of an insulating supporting-strip *d*, extending longitudinally along the bottom of the frame and forming a part thereof. The switch-springs of each set are thus held at the bottom in the slots of said strip and project upward alongside the corresponding shaft and substantially parallel therewith. The spring nearest the shaft normally rests upon a flat portion of the cam-piece *a'*, carried by the shaft, and when the shaft is rotated the corner of said cam-piece pushes this spring over in the direction of the general longitudinal axis of the structure. In the key shown each set of switch-springs comprises two movable strips and two other strips carrying contact-anvils therefor. Normally the strips are separated from their contact-anvils; but when the shaft is rotated the cam *a'* shifts the movable strips (which are arranged to move together by means of an interposed insulating-stud *e*) into contact with the anvils carried by the other strips. Each strip is suitably insulated from its neighbor. The "sticking-magnet" is mounted alongside the row of actuating-shafts. This magnet may be constructed with a single coil of wire *m'*, disposed within the core *m*, of E-shaped cross-section, as shown in Fig. 5. Each shaft may be provided with an armature-bar *f*, carried thereby on the other side of said shaft from the switch-springs *c* in such position that when the shaft is rotated to actuate the switch-springs the armature-bar will be swung laterally over against the polar faces of the magnet. In accordance with a well-known system the magnet will be energized until the called subscriber answers, so that the key once actuated will be held over to apply the ringing-current continuously until the called party shall respond, after which the magnet will be deenergized and permit the shaft to return to its normal position, which it will do by reason of the elasticity of the switch-springs bearing upon the cam-piece *a'*.

It is desirable that party-line ringing-keys should have, in addition to the individual switch-springs which apply the specialized current, certain other switch-springs serving, for example, to interrupt the cord-circuit to be actuated in the actuation of any one of the individual switches which control the application of the specialized ringing-current, and I have therefore provided such general springs in my key to be actuated through the agency of a longitudinally-sliding rod *g* whenever any one of the shafts *a* is rotated. Said rod carries pins *g'*, which project in position to be engaged by the several cam-pieces *a'* of the key-shafts, so that when any one of said key-shafts is turned the rod *g* will be moved longitudinally. This rod may carry pieces *g'' g'''* of insulating material arranged to actuate the sets of switch-springs *h h'*, which may be mounted in slots in the insulating supporting-strip *d* in a manner similar to the mounting of the individual sets of switch-springs *c c*.

It will be appreciated that the structure shown and described is extremely compact, so that it will take up very little space, either laterally or in depth, in the key-shelf. The keys while not liable to accidental operation will nevertheless be easy for the operator to manipulate, and when any key is actuated the crank-lever on the face of the board will serve as an indicator, so that the merest glance will show which key has been operated.

I claim—

1. A switch-key comprising a supporting-frame, a vertical shaft mounted to rock in bearings in said frame, a crank-lever carried by the upper end of said shaft, a set of switch-springs mounted at the bottom of the frame and extending up alongside the shaft, substantially parallel therewith, a cam-piece carried by the shaft adapted to move the switch-springs when the shaft is rotated, an armature carried by the shaft, and a magnet having a polar face at the side of said shaft adapted to engage and hold the armature when the shaft is turned, to hold the key in its actuated position.

2. A party-line ringing-key for the horizontal key-shelf of a telephone-exchange switchboard, comprising a supporting-frame, a series of actuating-shafts mounted vertically to rock in bearings in said frame, a horizontally-projecting crank-arm carried by each shaft above the supporting-frame, switch-springs mounted in association with each shaft, a part carried by each shaft in position to move the corresponding switch-springs when the shaft is rotated, an electromagnet having a pole-piece extended alongside the row of actuating-shafts, and an armature carried by each shaft adapted to be moved against the face of the magnet-pole as the shaft is rocked, whereby the key may be held in its actuated position by the magnet.

3. A party-line ringing-key for telephone-

switchboards, comprising a supporting-frame, a row of vertical actuating-shafts mounted to rock in bearings in the supporting-frame, an insulating-strip along the bottom of the frame, 5 said strip having transverse vertical slots at intervals between the actuating-shafts, sets of switch-springs held edgewise in said slots between the shafts and substantially parallel therewith, and a cam carried by each shaft, 10 adapted when the shaft is rotated to move the corresponding switch-springs.

4. A multiple key for telephone - switchboards comprising a supporting-frame, a series of vertical shafts mounted to rock in bearings 15 in said frame, each shaft having a crank-lever projecting horizontally therefrom above the top of the frame, an insulating-strip along the bottom of the frame, transverse vertical slots in said strip adjacent to the several shafts, 20 sets of switch-springs held edgewise in said slots, each set extending up alongside the corresponding shaft, a cam carried by each shaft in position to move the associated switch-springs when the shaft is rotated, a magnet 25 having polar faces extended longitudinally alongside the several shafts, and a vertical armature-bar carried by each shaft on the opposite side thereof from the switch-springs, adapted when the shaft is rotated to engage 30 the polar faces of the magnet, whereby any key when once actuated may be held over by the magnet.

5. A switch - key for telephone - exchange switchboards comprising a supporting-frame, 35 a vertical shaft mounted to rock in bearings in said frame, a crank-lever carried by the shaft above the supporting-frame, switch-springs supported by the frame, a cam carried

by the shaft adapted when the same is rocked to move said switch-springs, and a magnetic 40 lock adapted when the shaft is rocked to hold the same in such position.

6. A switch-key for a telephone-switchboard comprising a supporting-frame, an actuating-shaft mounted vertically to rock in bearings 45 in said frame, a horizontally-projecting crank-arm carried by the shaft above the frame, an insulating-strip along the bottom of the frame, switch-springs supported by said strip, a cam carried by the shaft adapted when the same is 50 rocked to actuate the switch-springs, an armature carried by the shaft, and a magnet having a polar face adapted to engage and hold the armature when the shaft is turned to lock the shaft in such position. 55

7. A switch-key for a telephone-exchange comprising a supporting-frame, an actuating-shaft mounted to rock in bearings in said frame, a horizontally-projecting crank-arm carried by the shaft above the supporting- 60 frame, an insulating-strip along the bottom of the frame, said strip having slots therein adjacent to said shaft, switch-springs held in said slots parallel to said shaft, a cam carried by the shaft adapted when the shaft is rocked to 65 actuate said springs, an armature carried by the shaft, and a magnet having a polar face at the side of said shaft adapted to engage and hold the armature when the shaft is turned to lock the shaft in its actuated position. 70

In witness whereof I hereunto subscribe my name this 10th day of November, A. D. 1902.

FREDERICK H. LOVERIDGE.
